UNITED STATES PATENT OFFICE

WALTER P. GISSKE, OF CHICAGO, ILLINOIS, ASSIGNOR TO VAUGHAN NOVELTY MFG. CO.,
OF CHICAGO, ILLINOIS, A CORPORATION OF ILLINOIS

CAN OPENER

Application filed February 24, 1931. Serial No. 517,872.

This invention relates to improvements in can openers, and more particularly to can openers having a handle for firmly holding the same with one hand by operating the cutting mechanism with the other to cut the top from a can.

The object of the present invention is to provide an improved design for can openers of the handle type which will insure positive and dependable cutting action. Bearing in mind that the can is not held in the hand during the cutting operation, it is therefore essential that the opener be equipped with members which will take the place of the hand and bring about the application of forces which will insure a smooth and positive cutting operation.

A preferred embodiment of the invention is disclosed in the accompanying drawings, in which

Figure 1 is a view in side elevation of the one style of the can opener.

Figure 2 is a view of the same opener in end elevation.

Figure 3 is a view in side elevation of the opener shown in Figure 1 taken from the opposite side.

Figure 4 is a view in side elevation of a modified type of opener with the blade shifted to inoperative position.

Figure 5 is a view similar to Figure 1 with the blade in cutting position, and

Figure 6 is a view in end elevation of the same opener taken from the opposite side.

Referring to the opener shown in Figures 1 to 3, the operating parts are located at the outer end of a handle 1 preferably of wood and of a size and shape to be held securely in the hand. Mounted in one end of the handle 1 is a relatively fixed blade-like arm projecting endwise from the end thereof, and pivotally connected with the end of the arm is a plate 3 extending at right angles to the handle 1 and arm 2, and connected with the latter by a pin 4 passing through their overlapping end portions.

The outer end portion of the arm 2 is increased in width over the short shank portion adjacent the handle and this wider portion has a straight bottom edge 2a which

forms an abutment for two cylindric lugs 5, 5 projecting from the rear face of the plate 3 and located on either side of a vertical line through the center of the pivot pin 4 (Figure 3). These lugs are of different diameters and are so located as to permit a limited angular movement of the plate 3 relative to the arm 2 as shown in dotted lines (Figure 3).

The plate 3 is elongated in a direction 60 transverse to the handle 1 and arm 2, and journalled near its lower end is a toothed traction wheel 6 lying flatwise in close contact with the front face of the plate, and on the opposite side is a handle member 7 fixed 65 to the wheel so that they turn together. The handle member is of the finger operative type, having two oppositely disposed radial arms or finger pieces 7a, 7a. At the lower edge of the plate 3 and spaced a short distance from 70 the periphery of the traction wheel is a lug 8 projecting a short distance beyond the face of said disc.

Above the traction wheel is a cutting or shearing lever 9 journalled on the pivot pin 75 4 which joins the plate 3 with the arm 1. The cutting lever has a long arm extending upwardly some distance beyond the upper edge of the arm and is surmounted by a laterally facing finger piece 9a. The relatively 80 short arm extending below the pivot pin is shaped to form a shearing blade 10 defined by the oblique edges meeting in a point which projects downwardly and just overlaps the toothed edge of the wheel when in cutting 85 position, the pointed end of the blade being offset from the plate 3 in order to clear and overlie the edge of the wheel. The blade is in shearing or cutting position when the lever is vertical, and particularly when its inner 90 edge contacts with an abutment or vertical shoulder 11 formed by slotting the upper edge of the plate on the side of the cutting lever adjacent the handle 1 and bending the metal outwardly into the path of the lever. 95

On opposite sides of the cutting lever 9 are fingers 12 and 13 extending at right angles to the plate 3 and from the side on which the traction wheel is located. The outermost finger 12 is an integral portion at 100

the outer edge of the plate 3 bent at right angles, while the innermost finger 13 is an integral part of the arm 2 at the inner end of the widened end portion and which is also bent at right angles. The lower edges of these fingers 12 and 13 coincide with a line substantially parallel with the axis of the handle 1.

As clearly shown in Figure 2, the ordinary type of can has a flange *f* around its rim which projects edgewise and also laterally in the form of a rounded bead. Now, to insert the can into the opener, the handle of the cutting lever is pressed forwardly thus shifting the cutting blade away from the traction wheel 6 and out of its cutting position. The rim of the can is then placed against the plate so that its top edge bears against the fingers 12 and 13, and the lower edge rests upon the periphery of the wheel. The cutting lever is now swung forwardly carrying the point of the cutting blade into contact with the top of the can just inwardly from the rim thereof. The lever is not quite vertical, however, but by turning the wheel in a counter-clockwise direction (Figure 1) rotates the can in the same direction, and swings the lever into its vertical position against the abutment 11, at the same time causing the point of the blade to puncture the top and thus starting the cut.

Now, by continuing the turning of the wheel, the can rotates bodily and the top thereof is sheared as it makes a complete revolution, leaving a smooth inner edge about the opening. During the opening operation the can is held upright and preferably just over or resting lightly on the surface of a table so that after the top has been cut the opener may be detached without danger of the can dropping.

The features to be emphasized in the action of the opener are the limited pivotal movement between the arm 2 and plate 3, and the fingers bearing upon the rim of the can, the combined action being such that the can is continually forced against the traction wheel, thus insuring the rotative movement essential to the shearing of the top. Moreover, the pivotal connection between the arm 2 and plate 3 with their respective fingers 12 and 13 promotes greater adaptability to cans of different sizes and cans with rims of varying height.

Figures 4, 5 and 6 show a modified construction of an opener differing from the previously described type in the form of cutting lever used. Assuming for sake of brevity that the two openers are otherwise substantially the same in construction and operation, the modified feature will be described. In this case the lever is a strip of tool steel bent in U-shape to straddle the plate 15 and pivotally mounted thereon by a pin 16 with its apex just clearing the upper edge thereof. The ends of the U-shaped lever extend down-

wardly, one end on the side of the traction wheel forming the cutting blade 14a as before, while the end on the opposite side of the plate is cut to form a gear sector 14b. Meshing with the gear sector is a gear member 17 fixed to and rotating with the handle member 18.

Thus as shown in Figures 4 and 6, a slight turn of the handle 18 in a clockwise direction (Figure 4) swings the lever 14 to an inclined position with the blade 14a removed from the traction wheel 19 so that a can may be inserted into cutting position. The movement of the cutting blade, however, is limited to an arc of about 45° by the contact of the gear sector with the lower end of a shoulder 15a formed in the process of offsetting the end portion of the plate 15 adjacent the point of pivotal connection with the arm 20.

Thus when the can is in position with its beaded edge in contact with the traction wheel, it is only necessary to turn the handle 19 in the opposite or counter-clockwise direction (Figure 4) and the lever 14 is brought into cutting position, and continued movement results in first the puncturing of the can top, and then the shearing cut as before. The lever is brought to rest and held in its vertical cutting position by contact with the shoulder 15a, while the gear sector 14b passes 95 beyond and out of mesh with the gear wheel 17, so that the handle 18 and traction wheel 19 can be rotated freely.

Having set forth the novel features of my invention,

I claim:

1. A can opener comprising a handle, a plate pivotally mounted at one end of said handle for a limited movement relative thereto, a traction wheel journalled on said plate, a cutting lever pivotally mounted on said plate adjacent said traction wheel and co-acting therewith to cut around the top of a can as the same is rotated by contact with said traction wheel, and a pair of fingers, one on either side of said lever and extending at right angles to said plate, one of said fingers being mounted on said plate and the other on said handle.

2. A can opener comprising a handle for holding the opener in one hand and having a blade-like arm at one end, a plate pivotally connected with said arm for limited angular relative displacement in flatwise contact with each other, a hand-operable traction wheel journalled on said plate, a cutting blade pivotally mounted on said plate adjacent said wheel and adapted to be swung into and out of cutting position, and a pair of fingers on opposite sides of said cutting blade, one being formed integral with said plate and the other with said arm, and operative to engage the rim of a can ahead and behind the cutting blade during the cutting operation.

3. A can opener comprising a handle member having a blade-like arm extending from one end, a plate pivotally connected in flat-wise contact with said arm and extending 5 at right angles thereto, said plate and arm having coacting stop members for limiting the relative angular displacement, a traction wheel journalled on one side of said plate, a cutting blade pivotally mounted adjacent 10 said wheel and adapted to overlie the periphery thereof in cutting position, and a pair of fingers disposed on opposite sides of said cutting blade, one being formed integral with said plate and the other with 15 said arm, said fingers being adapted to act as abutments for the edge of a can as the same is being opened.

4. A can opener comprising a frame, coacting manually operated cutting mechanism 20 mounted on said frame, a handle pivotally connected with said frame and adapted to be held in one hand to support the opener while operating the cutting mechanism with the other, and guide members spaced apart 25 on opposite sides of the cutting mechanism during the cutting operation, one of said members being on the frame and the other on the handle.

5. A can opener comprising a frame, cutting members including a cutter and a traction wheel mounted on said frame, a handle pivotally connected with said frame for limited angular movement relative thereto, a guide member on said frame and a corresponding guide member on said handle, said 35 members being adapted to bear upon the rim of the can on opposite sides of the cutter during the cutting operation.

Signed at Chicago, Ill., this 18th day of
40 February, 1981.

WALTER P. GISSKE.
